UNITED STATES PATENT OFFICE.

CHARLES E. GREEN, OF NEWARK, NEW YORK, ASSIGNOR OF ONE-HALF TO CHARLES T. BLOOMER, OF NEWARK, NEW YORK.

CORNER CONSTRUCTION FOR BOXES.

1,158,802.

Specification of Letters Patent.

Patented Nov. 2, 1915.

Application filed March 3, 1915. Serial No. 11,762.

To all whom it may concern:

Be it known that I, CHARLES E. GREEN, a citizen of the United States, residing at Newark, in the county of Wayne and State of New York, have invented a new and useful Corner Construction for Boxes, of which the following is a specification.

The present invention appertains to boxes, and more particularly to a corner construction for paper, cardboard and similar boxes, such as are commonly employed for carrying or conveying suits of clothes, and the like, although the corner construction may be employed in boxes of various characters. Boxes used at the present day for carrying suits of clothes, and the like, usually have the walls thereof connected together at the corners by means of tongues, flaps or hooks engaged through slits, or other similar fastening means are used, but these have been found to be of disadvantage and annoyance, since the box will readily break or burst open. In other words, the corner constructions of prevailing boxes, used for the conveyance and storage of clothes, and the like, are too weak and inadequate for the purposes, and it is the object of the present invention to provide a novel and improved corner construction for paper, cardboard or similar boxes, which will be thoroughly substantial so as to withstand the wear and tear, and strains to which the box is subjected in use.

It is also the object of the invention to provide the adjacent walls of the box with unique interengageable portions or members which may be interlocked for securing the walls of the box together in a firm manner, and whereby the box may be handled in blank form prior to the use thereof, and in order that the box may be readily erected for use.

It is also within the scope of the invention, to provide a corner construction for boxes of the nature indicated, which will be comparatively simple, noncumbersome and inexpensive in construction, which will not require excessive or additional stock to be employed or which will lie within the outline of the blank box, and which will be convenient, efficient and thoroughly practical in use.

With the foregoing and other objects in view which will appear as the description proceeds, the invention resides in the com-

bination and arrangement of parts and in the details of construction hereinafter described and claimed, it being understood that changes in the precise embodiment of the invention herein disclosed can be made within the scope of what is claimed, without departing from the spirit of the invention.

The invention is illustrated in its preferred embodiment in the accompanying drawing, wherein:

Figure 1 is a perspective view of one corner of a box illustrating two adjacent walls of the box secured together by means of the improved corner construction. Fig. 2 is a fragmentary plan view of one corner of the blank from which the box is folded. Fig. 3 is a view similar to Fig. 2 illustrating the parts of the adjacent walls as being folded and secured ready for the interlocking of the two walls with each other. Fig. 4 is a sectional detail through the corner of the box, on the line 4—4 of Fig. 1. Fig. 5 is a perspective view of the corner of the box, with the adjacent walls unlocked or detached.

It may be stated at the outset, that clothing boxes usually comprise a receptacle or tray, and a cover therefor, which are of duplicate construction, and it will therefore be obvious that the present invention may be employed in the cover or lid as well as in the box or receptacle proper, and for the purpose of convenience, the invention will be described as employed in the box or receptacle, although it is to be understood that the corner construction may be employed in various boxes, covers, and the like.

The present box is formed from a blank of paper, cardboard or similar flexible stock, as usual, and since the present invention resides in the corner construction, only one corner of the box is illustrated, although it will be evident that the present invention may be employed for each corner of the box. The blank embodies the body 1 which forms the bottom of the box when the blank is folded, and the body 1 of the blank has portions which are folded upward to provide the side walls of the box, only two of the portions or side walls 2 and 3 being illustrated.

In carrying out the invention, reference being had particularly to Fig. 2 wherein the construction is illustrated in blank form, the

end of the wall 3 adjacent the adjacent wall 2 is provided with a tapered or approximately triangular flap 4 projecting therefrom, the free end of the flap 4 being cut off, as at 5, and there being a fold line 6 between the wall 3 and the base of the flap 4.

The adjacent end of the wall 2 has a flap 7 projecting therefrom adjacent the flap 4, the two flaps being separated by a slit or cut extending to the corner of the body or bottom 1 between the walls 2 and 3, and there is also a fold line 8 between the wall 2 and base of the flap 7. The flap 7 is provided with a portion 9, which is foldable back against the outer side of the body portion of the flap 7, upon the diagonal or oblique fold line 10 extending from the free end of the flap 4 to that side of the base of the flap 7 remote from the flap 4. That edge portion of the portion or supplemental flap 9 of the flap 7 which is remote from the flap 4, is provided with a recess or notch 11.

When the blank is cut or struck from the stock, the flaps 4 and 7 may be readily formed therein, and it will be noted that the flaps lie within the outline of the blank, in order that excessive or additional stock will not be required. This is of advantage, since the waste incident to ordinary corner fasteners is eliminated.

The flaps 4 and 7 are then bent or folded to provide the interengageable portions or members carried by the adjacent ends of the adjacent walls 2 and 3, and to this end the flap 4 is folded back or reflexed against the inner side of the wall 3 parallel therewith, and a staple or other securing element 12 is engaged through the basal portion of the flap 4 and the wall 3 between the side edges of the said flap. The staple or securing means 12 therefore holds the flap 4 in place adjacent the inner side of the wall 3 of the box with the flap 4 projecting inwardly or away from the respective end of the wall 3.

The portion 9 of the flap 7 is folded back against the outer side of the body portion of the flap 7, upon the fold line 10, the body portion of the flap 7 and the portion 9 being of triangular contour and coinciding when they are folded together, and a staple or securing element 13 is then driven or engaged through the body portion of the flap 7 and the portion 9 of the said flap adjacent the apices of the said portions. Thus, the portions of the flap 7 will be secured or held together, and will provide a triangular pocket 14 whose mouth is disposed adjacent the end of the wall 2 and which pocket opens outwardly and away from the wall 3 of the box. It will be noted that the body portion of the flap 7 provides the inner side of the pocket 14, while the portion 9 of the said flap provides the other side of the said pocket, the outer side of the pocket or por-

tion 9 having the recess or notch 11 adjacent and extending away from the mouth of the pocket. The doubled flap 7 extends at right angles from the wall 2.

The parts are thus secured together by the staples or securing means 12 and 13 at the factory, and the box may still remain in blank form, in order that the blanks may be stacked or bundled as usual, and without requiring the boxes to be erected before it is necessary or desirable to use them. With the parts secured together as illustrated in Fig. 3, and as above described, the side walls 2 and 3 of the box may be readily and effectively secured or locked together for holding the walls 2 and 3 together in a firm and efficient manner. To attach the side walls 2 and 3 together, they are folded upwardly at an angle to the bottom 1, and the parts are properly manipulated to insert the reflexed or bent back flap 4 into the pocket 14, whereby the pocket which is bent inwardly will snugly receive the flap or tongue 4 and rest against the inner side of the wall 3. The flap 4 is engaged within the pocket 14 by swinging the wall 2 inward toward the bottom 1 after the wall 3 has been swung to erect position, perpendicular within the bottom 1, and which will bring the pocket 14 to such a position adjacent or beyond the free portion of the flap 4, to allow the flap 4 to be readily received by the pocket 14 when the wall 2 is swung back to upright or erect position. The recess or notch 11 of the portion 9 will receive and accommodate the staple or securing element 12, while the cut away portion 5 of the flap 4 will prevent the flap 4 from interfering with the staple 13 at the apex of the pocket and in order that the members of the side walls may be properly and effectively interlocked.

The corner of the box, when the side walls are attached together, will be thoroughly substantial and will not be liable to break or burst open when outward pressure is exerted against the side walls of the box. Since the pocket 14 of the side wall 2 is engaged over the flap 4 of the wall 3, with the portion 9 projecting between the flap 4 and wall 3 beyond the staple 12, the wall 2 cannot swing outward, and since the flap 4 of the wall 3 is received in the pocket 14 of the wall 2, the wall 3 cannot swing outward, and as a consequence, the interengagement of the members of the walls 2 and 3 will efficiently hold the walls against separation, and the parts will not be liable to tear loose, as is frequently the case with the ordinary fasteners of clothing and similar boxes.

Particular attention is directed to the fact that the doubled portion 7-9 which is located at the inner side of the wall 3 projects angularly in one direction from the wall 2, and is provided with the pocket 14 opening in the opposite direction at the basal por-

tion of the doubled portion, whereby the bent back flap 4 at the end of the wall 3 and located at the inner side of said wall fitting in said pocket, will thereby hold said walls 5 against separation, the flap 4 projecting in the same direction as the doubled portion.

From the foregoing, taken in connection with the drawing, the many advantages and capabilities of the present invention will 10 suggest themselves to those versed in the art and further comment is deemed unnecessary.

Having thus described the invention, what is claimed as new is:—

15 1. In a device of the character described, a body having adjacent walls, one wall having a portion at the inner side of the other wall and projecting angularly in one direction from the first mentioned wall, and said portion having a pocket opening in the opposite direction, the second mentioned wall having a portion at its inner side projecting in the same direction as the first mentioned portion and adapted to fit in said pocket, 20 whereby the walls are thereby held against separation and outward movement.

25 2. In a device of the character described, a body having adjacent walls, one wall having a doubled portion at one end and at the inner side of the other wall and projecting angularly in one direction from the first mentioned wall, said doubled portion providing a pocket opening in the opposite direction, the second mentioned wall having a portion bent back from one end and located 30 at the inner side thereof, said bent back portion projecting in the same direction as the doubled portion and being adapted to fit in said pocket, whereby the walls are thereby held against separation and outward movement.

35 3. In a device of the character described, a body having adjacent walls, one wall having a doubled portion at one end and at the inner side of the other wall and projecting angularly in one direction from the first mentioned wall, said doubled portion providing a pocket opening in the opposite direction, the second mentioned wall having a portion bent back from one end and located 40 at the inner side thereof, said bent back portion projecting in the same direction as the doubled portion and being adapted to fit in said pocket, whereby the walls are thereby held against separation and outward movement.

40 3. In a device of the character described,

a body having adjacent walls, one wall having a doubled portion at one end and at the inner side of the other wall and projecting 45 angularly in one direction from the first mentioned wall, said doubled portion providing a pocket opening in the opposite direction, the second mentioned wall having a portion bent back from one end and located 50 at the inner side thereof, said bent back portion projecting in the same direction as the doubled portion and being adapted to fit in said pocket, whereby the walls are thereby held against separation and outward 55 movement, a securing element engaged through the doubled portion, and a securing element engaged through the bent back portion and second mentioned wall, the doubled portion having a recess for accommodating 60 the second mentioned securing element.

4. In a device of the character described, a body having a pair of adjacent walls, one wall having a flap at one end bent back thereagainst, a securing element engaged 65 through the basal portion of the flap and the said wall, the other wall having a flap at one end adjacent the aforesaid flap, the last mentioned flap being doubled upon a diagonal fold line to provide a pocket for receiving the first mentioned flap, the pocket and first mentioned flap being approximately triangular in contour, a securing element engaged through the sides of the pocket adjacent the apex thereof, and one side of the 70 pocket having a recess for receiving the first mentioned securing element.

In testimony that I claim the foregoing as my own, I have hereto affixed my signature in the presence of two witnesses.
